UNITED STATES PATENT OFFICE.

WILLIAM H. NICHOLLS, OF BROOKLYN, NEW YORK, ASSIGNOR TO WM. H. NICHOLLS CO., INC., OF BROOKLYN, NEW YORK, A CORPORATION OF NEW YORK.

MOLDING-MACHINE.

1,277,745.

Specification of Letters Patent. Patented Sept. 3, 1918.

Application filed July 11, 1916. Serial No. 108,620.

To all whom it may concern:

Be it known that I, WILLIAM H. NICHOLLS, a citizen of the United States, and a resident of Brooklyn, county of Kings, and 5 State of New York, have invented certain new and useful Improvements in Molding Machines, of which the following is a full, clear, and exact description.

This invention relates more particularly 10 to a machine for mechanically squeezing or pressing the sand about a pattern or patterns within a flask or flask member thereof.

One of the principal objects of the invention is to provide a simple and efficient machine wherein the cope member of a flask or 15 a flask frame may be supported upon a plate about one or more patterns and the parts forming a mounting therefor given a rapid reciprocatory movement to initially pack or 20 arrange the sand about the pattern or patterns within the flask frame or member and the sand squeezed and the pattern stripped from the mold entirely automatic.

Another object of the invention is to provide 25 simple and efficient means whereby a flask or flask member may have the sand squeezed about a pattern and the pattern stripped from the mold during a single up and down movement of the flask member 30 and the mounting therefor.

Other objects of the invention are to provide 35 a simple and efficient mounting for the different parts of the machine; to provide simple and efficient means whereby a pattern plate may have a plurality of patterns mounted thereon, and the said patterns so held that a relative movement may be given to the pattern plate with respect to a stripper plate; to provide simple and efficient 40 means whereby annular patterns may be employed; to provide simple means whereby the pressure within the flask or flask member may be automatically released without mechanically lowering the flask from the 45 pressing means; to provide effective means whereby the parts may be jolted; and to provide simple means whereby the flask or flask member may be held in an elevated position and permitted to lower independent of the 50 lowering of other parts coöperating therewith.

A further object of the invention is to provide 55 a molding machine in which the cope or the flask frame and the pattern may be first agitated to pack the sand about the pat-

terns and the patterns and flask given an elevated movement and the sand squeezed about the patterns and the patterns automatically stripped from the molds and the parts restored to a normal position, all actuated or controlled by a fluid pressure, as air, and said fluid pressure controlled by a single valve.

A still further object of the invention is to provide simple and efficient means for supporting the various parts on which the flask and patterns are mounted, so that there will be no unnecessary vibration to disturb the mold after the sand has been squeezed about the pattern or patterns.

A still further object of the invention is to provide a molding machine which is adapted to form molds of different kinds, and is adapted for either single or divided flasks.

With these and other objects in view, the invention will be hereinafter more particularly described with reference to the accompanying drawings, which form a part of this application, and will then be pointed out in the claims at the end of the description.

In the drawings, Figure 1 is a vertical section, partly in elevation, of one form of machine embodying the invention.

Fig. 2 is a section plan taken on the line II—II of Fig. 1.

Fig. 3 is a sectional plan taken on the line III—III of Fig. 1.

Fig. 4 is a sectional plan taken on the line IV—IV of Fig. 1.

Fig. 5 is a fragmentary sectional plan taken on the line V—V of Fig. 1.

Fig. 6 is a fragmentary vertical transverse section taken on the line VI—VI of Fig. 1.

Fig. 7 is a fragmentary transverse section on a larger scale showing how annular patterns may be supported to have a movement relative to a stripper plate or member.

Fig. 8 is a detail sectional plan of one form of valve which may be used to control the fluid pressure supply.

Fig. 9 is an inverted detail plan of the valve.

Fig. 10 is an inverted plan of the valve casing and the connections for controlling the movements of the different parts of the machine.

Fig. 11 is a sectional elevation of the controlling valve; and

Fig. 12 is an enlarged fragmentary sec-

tion showing how the large piston is constructed to prevent leakage of air or other actuating medium.

While the invention is shown as applied 5 more particularly to form the molds for casting annular copper bands or rings, it will be understood that the character of the pattern or the number thereof may be changed and that the machine as a whole is 10 adapted for various purposes, and that certain features of the machine may be employed in connection with molding machines of different kinds or constructions.

In the general form of machine shown, 15 the cope or flask frame is supported upon a stripper plate under a pressure member, and at a distance therefrom and extending through the stripper plate are annular patterns. These patterns, there being three 20 shown though this number may vary, are mounted upon a pattern plate and this pattern plate is supported upon a reciprocatory head. This head also supports and guides a frame to which the stripper plate is held. 25 The head on which is mounted the flask frame, stripper plate, patterns and frame, has a part thereof forming a piston which is adapted to work within a second piston, the latter being movable vertically in a cylinder forming a part of the machine base. The two pistons are actuated by compressed air which is controlled by a single valve so that by placing the valve in one position the smaller piston will be reciprocated very 35 rapidly causing the patterns and flask frame to be also reciprocated rapidly, and by reason of the contact of the head with the upper end of the larger piston at each reciprocation a jar or jolt will be imparted to 40 the flask so as to arrange the sand properly about the patterns. By placing the valve in another position the larger piston is moved upwardly by the pressure of air so as to carry the smaller piston, the head, patterns and flask frame against a pressure foot, head, or member to squeeze the sand about the pattern to form the mold. If the valve is placed in another position the air acting 45 on the larger piston is exhausted and this permits all the parts to lower and after moving a short distance the stripper plate and flask frame are held in an elevated position at a point to relieve the pressure by the foot or head on the mold. The pistons 50 and pattern plate continue to lower, and as the mold and support are held against further movement the patterns will be stripped from the mold, allowing the latter to be removed from the machine and another placed in its stead. If the means for holding the stripper plate in its elevated position is released the stripper plate forming a mounting for the flask frame is permitted to lower by gravity to its former or normal 55 position, which will cause the patterns to be

projected above the upper surface of the stripper plate ready for the sand to be placed therein, if not already placed in the flask, and the operation repeated.

The machine shown has a base 10 at the upper portion of which is a cylindrical portion 11. Arms or brackets 12 and 13 extend outwardly therefrom, and may be formed integral with the base as a single casting or otherwise, as preferred. At the outer end 70 of the bracket or frame 12 is a boss 14 in which is rigidly held an upright or post 15, said post being held in the boss by means of a nut 16 on the lower end of said post. At the upper end of the post 15 are collars 17 and 18 between which is held a head or frame arm 19 which is adapted to be swung to one side of the machine with the post 15 as a pivot. The collar 17 may provide a ball or other bearing for the arm 19 and on the upper end of the post 15 is a nut 20 for rotatably holding the frame arm 19 on said post 15. The head or frame arm 19 has an enlarged portion at 20^a at one end, through which the post 15 passes, and at the other end thereof is provided with a boss 21 to which a rod 22 is rigidly held, as by means of the nuts 23 and 24. The lower end of the rod 22 is provided with a nut 25 and is adapted to enter a vertically arranged open slot 26 in the outer end 27 of the bracket or arm 13, and in such a way that the frame arm 19 may be swung with the rod 22 away from the bracket 13 or quickly positioned in the slot 26 as desired to resist vertical upward pressure against the arm 19.

A pressure member, foot or platen 28 is supported upon the frame arm 19. This pressure member 28 may be substantially rectangular in form to correspond to the shape of the cope or flask, and has projecting upwardly therefrom a threaded stem or portion 29. This stem 29 engages a threaded aperture in a part of the frame arm 19 so as to adapt the pressure member 28 to be 105 adjustable relatively to said arm 19. The pressure member or foot 28 is normally stationary, and is adapted to squeeze or press the sand about the pattern when the flask is forced upwardly, as will be presently described.

The cylindrical portion 11 of the base forms a cylinder 30 which has its upper end open and its lower end closed by a head 31. In the cylinder 30 is a cylinder piston 32, 120 which is adapted to have a vertical movement. This piston 32 is provided with an inner cylinder 33, the upper end of which is open, and in said cylinder 33 is a piston 34 of relatively small diameter as compared with the piston 32, and which is adapted to have an independent movement with respect to said piston 32. The piston 34 carries a head 35. This head 35 is disk-like in form and is adapted to rest normally upon the 125

upper end of the piston 32 or upon a rounded upper end of the cylinder 30. The head 35 is provided with two sets of lugs 36 and 37. There are four of each of said lugs, and these 5 lugs are radially arranged with respect to the center of said head. Projecting upwardly from the lugs 36 are posts 38, and mounted upon the upper end of said posts is a pattern plate 39. The pattern plate 39 is 10 secured by nuts 40 or otherwise to the posts 38 and held to said pattern plate are one or more patterns 41. As shown, there are three patterns, though this number may vary, and the particular form of patterns shown are 15 annular in form, although the shape or form of the pattern may be varied according to the character of the mold to be made. The patterns 41 project through annular slots in a stripper plate 43, on which is detachably 20 mounted or held the cope or flask frame 44. The flask or frame 44 is of the usual form, and may be provided with apertured lugs which are adapted to fit over pins 45 on the stripper plate 43, or may be otherwise held 25 thereon, as preferred. The stripper plate 43 and the patterns 41 with the pattern plate 39 are adapted to have a relative movement to adapt the patterns to be stripped from the mold, as will be presently described, and by 30 reason of the particular patterns shown being in the form of open ended cylinders, bands or rings, it is necessary that said patterns be held and supported in a peculiar way, otherwise the annular disk-like part of 35 the stripper plate could not be held in position. To effect this the stripper plate is provided with substantially U-shaped lugs 46, Fig. 7, which extend through slots 47 in the pattern plate and the patterns 41 are also 40 slotted as at 48, to correspond to the width of the lugs 46, as shown in Figs. 3 and 7. In this way the patterns, pattern plate and stripping plate are interlocked, and in such a way that the patterns may move relatively 45 with respect to the stripper plate or the latter with respect to the patterns and pattern plate.

The stripper plate 43 is mounted upon a substantially rectangular frame 49. This 50 frame 49 at the corners thereof is provided with bosses 50 and in these bosses project posts or rods 51 which extend upwardly from the lugs 37 of the head 35. These posts 55 51 form guides for the frame 49 and permit relative movement between the frame and said head. The frame 49 with the head 35, pattern plate 39, patterns 41, stripper plate 43, and flask frame 44 are adapted to have a movement in unison, or said frame 49 and 60 stripper plate 43 may have a relative downward movement with respect to said head 35 and pattern plate 39 in order that the patterns may be properly positioned with respect to the stripper plate, as shown in Fig. 65 1, or the pattern plate with the patterns may

be moved relatively to the stripper plate to adapt the patterns to be stripped from the mold.

The frame 49 is adapted to be held in an elevated position to permit the stripping of 70 the pattern from the mold after the sand has been squeezed about the patterns. For this purpose the frame 49 on two walls thereof is provided with racks 52, the teeth 53 of which are adapted to be engaged by the 75 teeth or dogs 54 located at the upper ends of levers 55 when the frame 49 is elevated. These levers 55 are pivoted at 56 to posts or studs 57 extending inwardly from the rear of the brackets 12 and 13, as shown in 80 Figs. 1 and 6. The lower ends of the levers 55 are connected by a cross bar 58 and to said cross bar is held a pedal 59. The levers 55 below their pivots 56 extend or incline rearwardly of the machine and transversely 85 of the axis of the pivots 56, as shown in Fig. 6, so that the weight thereof tends normally to throw the dogs 54 into engagement with the teeth 53 of the racks 52 without the use of springs. The teeth 54 on the levers 55 90 may be released from the teeth 53 on the racks 52 by depressing the pedal 59. The flask frame is placed upon the stripper plate 43 over the pins 45 so as to be properly held thereon, and in position for the patterns 41 95 to extend upwardly within the frame, as shown in Fig. 1, there being a semi-spherical body or element 60 arranged within each pattern if desired, to rest upon the upper surface of the stripper plate 43 to which it 100 may be secured by screws or otherwise. The element 60 avoids the necessity for filling the patterns both in and about the same entirely with sand and serves to back up the mold to prevent it from breaking while 105 stripping the patterns. This element 60 also provides a chamber for the escape of gases from the mold to the chamber while pouring the metal, and this is particularly desirable when making castings of copper. 110

To control the movements of the pistons 32 and 34 and parts mounted upon the head 35, various means may be employed. As shown, the head 31 is provided with an offset portion 61 forming a passage for the admission of air under pressure to the cylinder 30 to move the large piston 32, and to prevent the piston 32 from being forced entirely out of the cylinder 30 a rod 62 is held to the head 31 and is provided with an enlarged 115 part 63 which is adapted to prevent the piston from being forced too far and which serves as a stop therefor. The smaller piston 34 is provided with a head 64 and extending upwardly from the head 64 is a 120 pipe 65 to which leads a source of air supply through a flexible pipe 65a. The piston 34 is provided with a cylindrical extension 64a below the head 64 which is adapted normally to cover a small outlet or exhaust 125 66 130

in the cylinder 33, which permits air from the pipe 65 within the cylinder 33 below the head 64 of piston 34 to escape into the larger cylindrical piston 32 when the piston 34 has been raised until the lower end of the extension 64^a thereof is elevated above the said opening 66. A pipe 67 leads from the passage 61 through the large cylinder to the casing 68 of a valve 69 and connected to the casing 68 is the pipe 65^a and also a source of compressed air supply pipe 70. The valve in the casing 69 comprises a disk-shaped valve 71 having two openings or recesses 72 and 73 which extend a part of the thickness of said valve, as shown best in Fig. 11. The valve is provided with upwardly extending lugs 74 between which is adapted to fit arms or lugs 75 projecting outward from a stem 76. The stem 76 is rotatably held in the valve casing, and at the outer end is provided with an operating handle 77, there being a spring 78 within the valve casing tending normally to keep the valve to its seat. The valve casing is provided with four openings 79, 80, 81 and 82. The opening 79 connects with the pipe 65^a leading to the pipe 65 and the small cylinder, the opening 80 to the air supply, the opening 81 to the pipe 67 leading to the large cylinder 30, and the opening 82 to the exhaust, which may be controlled by a pet cock 83 to regulate the amount of the exhaust or in any other desired way, and thereby regulate the speed of the draw.

35. The pistons may either or both be actuated by any suitable pressure medium whether air, water, steam, or the like, and said pistons are adapted to have suitable packing to retain the pressure properly and prevent leakage. The smaller piston may have suitable packing rings 84 about the same, and the larger piston may have one or more packing rings 85. The packing ring 85 is of a special construction and is adapted to be forced or spread outwardly by the pressure of the medium within the cylinder 30. This packing 85 may be of any suitable material, and may have its ends overlapping and cut the same as an ordinary piston ring. The packing 85 fits neatly within an annular groove in the piston 32, and at the inner portion thereof is provided with an annular substantially V-shaped groove 86. This groove is opposed to an annular recess 87 in the piston 32 and this annular groove 87 connects by a channel 88 with the pressure end of the cylinder 30 so that air or other medium for moving the piston may pass through the channel 88 into the annular groove 87 and act upon the ring 85 to force the same outward to provide an effective bearing by the ring against the cylinder and retain the pressure within the cylinder during the squeezing operation. The packing ring 85 may be of such material and

the groove 86 may be of such shape that when the pressure within the cylinder 30 is exerted on the packing ring 85 it will spread the rear part of the packing ring sufficient to form a tight joint between the packing 70 and the piston and prevent all leakage past the ring.

The operation of the invention will be readily understood from the foregoing description when taken in connection with the accompanying drawings. The flask frame being placed upon the stripping plate 43 in the position shown in Fig. 1 with the other parts in the position shown in this figure and the pipe 70 connected to a source of air supply under pressure and the valve 71 by means of the handle 77 operated so as to connect through the passage 72 the pipe 70 and pipe 65^a leading to the small cylinder 33, it will be evident that the pressure under the head 64 of piston 34 will cause the piston 34 to be raised until the lower end of the extension 64^a of said piston uncovers the exhaust opening or channel 66. As soon as the exhaust takes place the piston 34 will again lower by reason of the weight of the parts thereon. This elevation and lowering will be repeated in rapid succession so that the flask frame, the stripper plate 43, the frame 49, and the patterns will be also reciprocated rapidly and by reason of the contact of the head 35 with the upper end of the large piston 32 a jar or jolt will be imparted to these parts on each reciprocation. This jarring or jolting effect can be continued at will until the sand is initially packed properly about and within the patterns 41. By moving the handle 77 so as to connect the air supply opening 80 with the opening 81 air under pressure will be permitted to pass through the pipe 67 and channel 61 into the large cylinder 30 below the head of the large piston 32. This pressure will elevate the large piston, which will carry with it the smaller piston 34 and all the parts mounted upon the head 35, including the flask, so that the sand may be squeezed about the patterns by means of the normally stationary head or foot 28, there being previously placed within the flask a loose packing board or member serving as the engaging means for the foot or member 28. During the upward movement of the frame 49 the teeth 53 on racks 52 will ride past the dogs 54 on levers 55. The threads 105 of the stem 29 of the foot 28 are of substantially the same pitch as the teeth 53 of the racks 52 and, therefore, by giving the foot 28 a half turn after the sand has been squeezed in the mold it will be observed that the frame 49, head 35, pattern plate 39, stripper plate 43 and the patterns will all move upwardly in unison slightly while there will be a partial disengagement or relative upward movement between the dogs 110

54 and the particular teeth 53 with which said dogs were engaged at the completion of the squeezing operation, this relative movement being equal to about one half the 5 length of a tooth. If the handle 77 is now moved so that the recess of the valve connects the pipe 67 with the exhaust opening 82, the piston 32 will move downwardly carrying with it the small piston 34, head 35, 10 flask frame, stripper plate and pattern plate with the patterns thereon until the partially disengaged teeth 53 are again engaged by the dogs 54. This slight downward movement of the parts in unison is sufficient to 15 relieve the mold of the pressure of foot 28 before the stripping of the patterns begins. When the teeth 53 and dogs 54 again engage the downward movement of the frame 49, stripper plate, and flask is arrested but the 20 pistons, head 35, and pattern plate continue to descend, thus causing a relative movement between the pattern plate and the stripper plate which results in withdrawing the patterns from the molds and causing the upper 25 edges of the patterns to lie substantially flush with the upper surface of the stripper plate 43. When the patterns are stripped from the mold the flask may be removed and another placed in its stead, and by forcing 30 the pedal 59 downwardly the dogs 54 of the lever 55 may be disengaged from the teeth of the racks 52 which will permit the frame 49 with the stripper plate 43 to lower, causing the patterns 41 to again project above 35 the stripper plate, as shown in Fig. 1, in position for the sand to be placed within the flask frame and the same operation repeated.

From the foregoing it will be evident that a simple and efficient machine is provided 40 whereby a rapid reciprocatory jolting or jarring action may be given to a cope or flask frame and the sand within the flask frame squeezed and the patterns stripped from the mold all under the control of a 45 single valve; that simple means is provided whereby the squeezing and withdrawing of the patterns is effected during a single up and down movement of the parts; that simple means is provided whereby molds of 50 annular or cylindrical objects are formed; that simple means is provided whereby the mold is prevented from collapsing or being injuriously affected by reason of the jarring of the parts, and that said machine is simple 55 in construction and may be readily made and assembled.

Having thus described my invention, I claim as new and desire to secure by Letters Patent:—

60 1. In a molding machine, the combination of a support, two pistons held in said support of relatively different diameters and adapted to move together or independently, a head carried by one of said pistons, 65 a frame supported by said head adapted to

have a relative movement thereon, a stripper plate supported by said frame and adapted to support a flask frame thereon, a pattern plate also supported by said head, patterns mounted on said plate, a pressure member, 70 releasable means adapted to hold the frame and stripper plate in an elevated position and to be released therefrom to adapt said stripper plate and frame to lower independently of the movement of the pattern plate and patterns, and means whereby the pistons may be moved in unison or one independently of the other to cause a relative movement between the stripper plate and the pattern plate and to impart a rapid 75 reciprocatory jarring action to both the stripper plate and pattern plate.

2. In a molding machine, the combination of a support, two pistons held in said support of relatively different diameters and 80 adapted to move together or independently, a frame operatively connected to one of the pistons to have a relative movement with respect thereto, a stripper plate supported by said frame and adapted to support a 85 flask frame thereon, a pattern plate also supported by said head, patterns mounted on said plate, a pressure member, releasable means adapted to hold the frame and stripper plate in an elevated position and to be 90 released therefrom to adapt said stripper plate and frame to lower independently of the movement of the pattern plate and patterns, and compressed air controlled means whereby the pistons may be moved in unison or one independently of the other to cause a relative movement between the stripper plate and the pattern plate and to impart a rapid reciprocatory jarring action to 95 both the stripper plate and pattern plate.

3. In a molding machine, the combination of pattern supporting means, pattern stripping means adapted to support a flask frame thereon, releasable means adapted to hold the stripping means in an elevated position 100 and to be released therefrom to adapt said stripping means to lower independently of the movement of the pattern supporting means, and means whereby the pattern supporting means and the stripping means may 105 be moved in unison or one independently of the other.

4. In a molding machine, the combination of a support, two pistons held in said support and adapted to move together or independently, a head carried by one of said pistons, a stripper plate supported by said head and adapted to support a flask frame thereon, a pattern plate also supported by 110 said head, a pressure member, releasable means adapted to hold the stripper plate in an elevated position and to be released therefrom to adapt the said stripper plate to lower independently of the movement of the pattern plate, and means whereby the 115

- pistons may be moved in unison or one independently of the other to cause a relative movement between the stripper plate and the pattern plate.
5. In a molding machine, the combination of a support, two pistons held in said support of relatively different diameters and adapted to move together or independently, a head carried by one of said pistons, a frame supported by said head adapted to have a relative movement thereon, a stripper plate supported by said frame and adapted to support a flask frame thereon, a pattern plate also supported by said head, an adjustable normally stationary pressure member, releasable means adapted to hold the frame and stripper plate in an elevated position and to be released therefrom to adapt said stripper plate and frame to lower independently of the movement of the pattern plate, and single valve controlled fluid pressure means whereby the pistons may be moved in unison or one independently of the other to cause a relative movement between the stripper plate and the pattern plate and to impart a rapid reciprocatory jarring action to both the stripper plate and pattern plate.
6. In a molding machine, the combination of a support, two pistons held in said support and adapted to move together or independently, a stripper plate adapted to support a flask frame thereon, a pattern plate, a pressure member, releasable means adapted to hold the stripper plate in an elevated position and to be released therefrom to adapt said stripper plate to lower independently of the movement of the pattern plate, and means whereby the pistons may be moved in unison or one independently of the other to cause a relative movement between the stripper plate and the pattern plate.
7. In a molding machine, the combination of a flask, a stripper plate, a pattern plate having a pattern thereon projecting through the stripper plate, and means for rapidly reciprocating said stripper plate and pattern plate in unison to impart a jarring movement to the molding devices, and means for reciprocating the pattern plate independently of the stripper plate to withdraw the pattern from the mold.
8. In a molding machine, the combination of a stripper plate, a flask frame supported on said stripper plate, a pattern plate having a pattern thereon normally projecting through the stripper plate, a pressure member, means whereby the stripper plate and pattern plate may be given a jarring movement in unison, means for moving said plates in unison into operative relation with the pressure member, and means for causing a relative movement between the stripper plate and pattern plate to withdraw the pattern from the mold.
9. In a molding machine, the combination of a flask frame supporting means, a pattern supporting means adapted to support a pattern within the flask frame, a pressure member, means for rapidly reciprocating the flask frame supporting means and pattern supporting means in unison to impart a jarring movement to the molding devices, means for moving the flask frame supporting means and the pattern supporting means toward the pressure member to squeeze sand about the pattern and means for causing a relative movement between the flask frame supporting means and the pattern supporting means when said means are moved away from said pressure member to withdraw the pattern from the mold.
10. In a molding machine, the combination of a frame, a stripper plate mounted thereon adapted to support a flask frame, a pattern plate having a plurality of annular patterns projecting through said stripper plate, a normally fixed pressure member, means for holding the stripper plate in an elevated position, and means whereby the stripper plate and patterns may be given a rapid reciprocatory movement and a distinct elevating movement to squeeze sand about the patterns and a relative movement permitted between the stripper plate and the patterns to withdraw the patterns from the mold.
11. In a molding machine, the combination of a stripper plate adapted to support a flask frame, a pattern plate having a pattern thereon, a normally fixed pressure member, means for holding the stripper plate in an elevated position, and means whereby the stripper plate and pattern may be given a movement to squeeze sand about the pattern and a relative movement permitted between the stripper plate and the pattern plate to withdraw the pattern from the mold.
12. In a molding machine, the combination of a stripper plate adapted to support a flask frame, a pattern plate having a plurality of annular patterns projecting through said stripper plate, a pressure member, and means whereby the stripper plate and patterns may be given a rapid reciprocatory movement and an elevating movement to squeeze sand about the patterns and a relative movement permitted between the stripper plate and the patterns to withdraw the patterns from the mold.
13. In a molding machine, the combination of a pressure member, means for supporting said pressure member, a stripper plate, a pattern plate having an annular pattern thereon projecting through said stripper plate, a plurality of substantially U-shaped lugs connecting the part of the stripper plate within the pattern to a part without said pattern, said pattern plate and pattern being slotted to permit the stripper plate to move relatively to the pattern plate.

- means for elevating the stripper plate and pattern plate in unison toward the pressure member, and means whereby a relative movement may be effected between the stripper plate and the pattern plate.
14. In a molding machine, the combination of a pressure means, means for supporting said pressure means, a stripper plate, a pattern plate having an annular pattern thereon projecting through said stripper plate, a plurality of lugs connecting the part of the stripper plate within the pattern to a part without said pattern and the parts constructed to permit the stripper plate to move relatively to the pattern plate, means for elevating the stripper plate and pattern plate in unison toward the pressure member, and means whereby a relative movement may be effected between the stripper plate and the pattern plate.
15. In a molding machine, the combination of a flask frame supporting means, pattern supporting means, pressure means, and means for imparting a mechanical jarring action to the flask frame supporting means and a distinct unitary movement of both the flask frame supporting means and the pattern supporting means toward the pressure means, and means whereby a relative movement may be given to the pattern supporting means and the flask frame supporting means.
16. In a molding machine, the combination of a flask frame supporting means, pattern supporting means, pressure means, and fluid pressure controlled means for imparting a mechanical jarring action to the flask frame supporting means and a distinct unitary movement of both the flask frame supporting means and the pattern supporting means toward the pressure means, and means whereby a relative movement may be given to the pattern supporting means and the flask frame supporting means to withdraw the pattern from the mold.
17. In a molding machine, the combination of a frame, a rotatable frame arm, a pressure foot having a threaded stem adjustable in said arm, means whereby the frame arm may be held against rotation on said frame, a pattern plate, a stripper plate adapted to support a flask frame and movable with the pattern plate toward the pressure foot, means for holding the stripper plate in an elevated position, and means whereby the pressure exerted by the pressure foot may be automatically released.
18. In a molding machine, the combination of a frame, a rotatable frame arm, a pressure foot having a threaded stem adjustable in said arm, a pattern plate, a stripper plate adapted to support a flask frame and movable with the pattern plate toward the pressure foot, and means whereby the pressure exerted by the pressure foot may be automatically released.
19. In a molding machine, the combination of a frame, a rotatable frame arm, a pressure foot adjustable in said arm, means whereby the frame arm may be held against rotation on said frame, a pattern plate, a stripper plate adapted to support a flask frame and movable with the pattern plate toward the pressure foot, and rack and dog means for releasably holding the stripper plate in an elevated position.
20. In a molding machine, the combination of a frame, a stripper plate mounted upon said frame to move therewith, a head having posts serving as guides for said frame, means for holding a flask frame on the stripper plate, a pattern plate rigidly held to said head, a pattern supported by said plate, a pressure member located above the stripper plate and pattern, a piston formed integral with said head, a second larger piston having a cylinder for said piston of the head, and means whereby the smaller piston may move to cause a rapid reciprocatory movement to be imparted to the flask frame, stripper plate and pattern plate and then both pistons in unison to squeeze the sand about the pattern, and means whereby a relative movement may be given to the stripper plate and the pattern plate to withdraw the pattern from the mold.
21. In a molding machine, the combination of a stripper plate adapted to support a flask frame, a head having posts serving as guides for said stripper plate, a pattern plate rigidly held to said head, a plurality of annular patterns supported by said plate, a pressure member located above the stripper plate and patterns, a piston movable with said head, a second larger piston having a cylinder for the first mentioned piston, and means whereby the smaller piston may move to cause a rapid reciprocatory movement to be imparted to the flask frame, stripper plate and pattern plate, and the two pistons moved in unison to squeeze the sand about the patterns, and means whereby a relative movement may be given to the stripper plate and the pattern plate to strip the patterns from the mold.
22. In a molding machine, the combination of a frame having a cylinder, a piston movable in said cylinder, a smaller cylinder formed integral with said piston, a piston movable within said smaller cylinder, said cylinder having an exhaust opening and a source of compressed air supply thereto, a source of air supply for the larger piston, mold forming means operatively connected to the pistons, and means whereby the pistons may be made to move in unison or independently to adapt the mold supporting means to be given a rapid reciprocatory, jarring action and a movement whereby sand may be squeezed to form a mold.

23. In a molding machine, the combination of a frame having a cylinder, a piston movable in said cylinder, a bolt for limiting the extent of movement of said piston, a smaller cylinder formed integral with said piston, a piston movable within said smaller cylinder, said cylinder having an exhaust opening and a source of compressed air supply thereto, a source of air supply for the larger piston, mold forming means operatively connected to the pistons, and means whereby the pistons may be made to move in unison or independently to adapt the mold supporting means to be given a rapid reciprocatory jarring action and a movement whereby sand may be squeezed to form a mold. 70
24. In a molding machine, the combination of a frame having a cylinder, a piston movable in said cylinder, a smaller cylinder located within said piston, a piston movable within said smaller cylinder, said cylinder having exhaust means and a source of fluid pressure supply, mold forming means operatively connected to the pistons, a pressure member, and means whereby the pistons may be made to move in unison or independently to adapt the mold supporting means to be given a rapid reciprocatory jarring action and a movement whereby sand may be squeezed. 75
25. In a molding machine, the combination of a frame having a base provided with a cylindrical portion forming a cylinder, a cylinder piston movable within said cylinder, a pressure member supported by said frame, said cylinder piston having a small cylinder substantially central thereof, a piston movable in said small cylinder, a head carried by said small piston, means for preventing too great movement of the large piston, means including a single valve controlled compressed air supply for supplying compressed air to move the pistons in unison or independently, a stripper plate, a relatively movable pattern plate mounted to have a relative movement or to move together with the movement of the pistons, and releasable means for holding the stripper plate in an elevated position. 80
26. In a molding machine, the combination of a frame having a base provided with a cylinder, a cylinder piston movable within said cylinder, a pressure member supported by said frame, said cylinder piston having a small cylinder within the same, a piston movable in said small cylinder, a head carried by said small piston, means to move the pistons in unison or independently, a stripper plate, a relatively movable pattern plate mounted to have a relative movement or to move together with the movement of the pistons, and releasable means for holding the stripper plate in an elevated position. 85
27. In a molding machine, the combination of a frame having a base, a cylinder in the base, a piston movable within said cylinder, a pressure member supported by said frame, said piston having a smaller cylinder within the same, a piston movable in said smaller cylinder, a head carried by the smaller piston, and a single valve controlled compressed air supply for supplying compressed air to move the pistons in unison or independently, a stripper plate, a relatively movable pattern plate mounted to have a relative movement or to move together with the movement of the pistons, and releasable means for holding the stripper plate in an elevated position. 90
28. In a molding machine, the combination of a support, a pressure member, a stripper plate, a relatively movable pattern plate, means for moving the pattern plate and stripper plate toward the pressure member, racks mounted to move with the stripper plate, levers having teeth adapted to engage the teeth of the racks, and a pedal for releasing the levers from the racks to adapt relative movement to be given to the stripper plate with respect to the pattern plate. 95
29. In a molding machine, the combination of a support, a pressure member, a stripper plate, a relatively movable pattern plate, means for moving the pattern plate and stripper plate toward the pressure member, and releasable dog and rack means for holding the stripper plate elevated. 100
30. In a molding machine, the combination of a support, a pressure member, a stripper plate, a relatively movable pattern plate, means for moving the pattern plate and stripper plate toward the pressure member, a rack mounted to move with the stripper plate, and a lever having a dog adapted to engage the teeth of the rack whereby relative movement may be given to the stripper plate with respect to the pattern plate. 105
31. In a molding machine, the combination of a support, a pressure member, a stripper plate, a relatively movable pattern plate, means for moving the pattern plate and stripper plate toward the pressure member, racks mounted to move with the stripper plate, and releasable levers having dogs adapted to engage the teeth of the racks. 110
32. In a molding machine, the combination of a frame, a frame arm mounted thereon, a pressure member having a threaded stem adjustably held in said frame arm, a stripper plate, a rack mounted to move with said stripper plate and having the teeth thereof of the same pitch as the threads of the stem of the pressure member, means adapted to engage the rack to hold the stripper plate in an elevated position, a pattern plate, and means for moving the pattern plate and stripper plate toward the pressure member, the pitch of the threads of the stem of the pressure member and the teeth of the 115

- rack being the same to adapt the pressure by the pressure foot to be released immediately the means engaging said rack is released.
5. 33. In a molding machine, the combination of a frame, a frame arm mounted thereon, a pressure member having a threaded stem adjustably held in said frame arm, a stripper plate, a rack mounted to move with said stripper plate, a dog adapted to engage the rack to hold the stripper plate in an elevated position, a pattern plate, and means for moving the pattern plate and stripper plate toward the pressure member, the pitch of the threads of the stem of the pressure member and the teeth of the rack being the same to adapt the pressure by the pressure foot to be released immediately the dog is released from said rack.
10. 34. In a molding machine, the combination of a frame, a frame arm mounted thereon, a pressure member having a threaded stem adjustably held in said frame arm, a stripper plate, a rack mounted to move with said stripper plate, a lever having a dog adapted to engage the rack to hold the stripper plate in an elevated position, a pattern plate, and means for moving the pattern plate and stripper plate toward the pressure member, the pitch of the threads of the stem of the pressure member and the pitch of the teeth of the rack being the same to adapt the pressure by the pressure foot to be released immediately the dog is released from said rack.
15. 35. In a molding machine, the combination of a pressure member, pattern supporting means, means for supporting a flask frame about the pattern, a valve casing, a valve movable in said casing and having a handle operatively connected to rotate the same, relatively movable pistons, and connections between the valve and the pistons to adapt one piston to be moved independent of the other or both pistons to be moved together.
20. 36. In a molding machine, the combination of molding means, and a single valve and connections between said valve and the molding means whereby the molding means may be given a rapid reciprocatory movement and the mold formed during a single up and down movement of said molding means.
25. 37. In a molding machine, the combination of a pressure member, pattern supporting means, means for supporting a flask frame about the pattern, a valve casing, a valve movable in said casing and having a handle operatively connected to rotate the same, relatively movable pistons and connections between the valve and the pistons and controlled by said valve to adapt one piston to be moved independent of the other, or both pistons to be moved together.
38. In a molding machine, the combination of molding means, a valve casing, a rotary valve movable in said casing, relatively movable pistons connected to the molding means, and connections between the valve and the pistons and controlled by the valve to adapt one piston to be moved independent of the other or both pistons moved together.
40. 39. In a machine of the character described, the combination of a support adapted to hold a flask frame thereon, a relatively movable pattern adapted to project above the support and within the frame, means for causing a relative movement between the pattern and the support, and a substantially semi-spherical element held to the support within the pattern adapted to form a chamber within the mold to avoid the necessity for filling the pattern entirely with sand and to back up the mold and serve as a chamber for the escape of gas while casting the metal.
45. 40. In a machine of the character described, the combination of a support adapted to hold a flask frame thereon, a relatively movable pattern adapted to project above the support and within the frame, means for causing a relative movement between the pattern and the support, and an element held to the support within the pattern adapted to form a chamber within the mold.
50. 41. In a molding machine, the combination of mold forming elements, pistons of relatively different diameters operatively connected to said elements, one piston working within the other, packing means between the two pistons, a cylinder for the larger piston, a source of pressure medium supply for the cylinder, a packing ring held to the larger piston to move outwardly thereon and having a grooved inner portion to adapt the packing to be spread, and means forming a connection with the pressure end of the cylinder to force the packing outwardly and to spread the inner portion thereof.
55. 42. In a molding machine, the combination of mold forming elements, a piston having an annular groove operatively connected to said elements, a cylinder for the piston, a source of pressure medium supply to the cylinder, a packing ring held in the annular groove of the piston to move outwardly therein and having a grooved inner portion to adapt the packing to be spread, and means forming a connection with the pressure end of the cylinder.
60. 43. In a molding machine, the combination of a pressure member, a pattern supporting means, means for supporting a flask frame about the pattern, fluid-pressure operated devices for moving the pattern supporting means and the flask frame support.

ing means toward and from said pressure member, a single valve, and connections between said valve and fluid pressure operated devices whereby the flask frame and pattern 5 may be given a jarring movement and a movement in unison toward said pressure member and a movement away from said pressure member.

44. In a molding machine, the combination 10 of a pressure member, a pattern supporting means, means for supporting a flask frame about the pattern, fluid pressure operated devices for moving the pattern supporting means and the flask supporting 15 means toward and from said pressure member, and a single valve and connections between said valve and fluid pressure operated devices whereby the flask frame and pattern may be given a jarring movement and 20 a movement in unison toward said pressure member and a movement away from said pressure member, and means for causing a relative movement between the flask frame supporting means and the pattern supporting 25 means to withdraw the pattern from the flask frame during the movement of the flask frame and pattern supporting means away from the pressure member.

45. In a molding machine, the combination 30 of a pressure member, pattern supporting means, means for supporting a flask frame about the pattern, a piston connected to said flask frame supporting means, a piston connected to the pattern supporting means, 35 a valve, and connections between the valve and said pistons and controlled by the valve to adapt one of the pistons to rapidly reciprocate the flask frame and pattern supporting means in unison and to reciprocate 40 the other of said pistons to move the flask frame and pattern supporting means toward and from the pressure member.

46. In a molding machine, the combination 45 of a pressure member, a pattern supporting means, a flask frame, means for supporting the flask frame about a pattern, relatively movable pistons connected to the pattern supporting means and flask frame supporting means, a valve casing, a connection 50 between said casing and a source of fluid pressure, an exhaust passage connecting said casing with the atmosphere, independent connections adapted to deliver a fluid pressure medium from said casing beneath said pistons, and a rotary valve in said casing controlling said connections to cause a rapid reciprocation of one of said pistons to impart a jarring movement to the flask and pattern supporting means in one 55 position of the valve, to move said pistons in unison toward the pressure member in another position thereof, and to open said exhaust passage to permit the pistons to

move away from the pressure member in another position thereof. 65

47. In a molding machine, the combination of a flask, flask supporting means, pattern supporting means, pressure means, means for moving the flask supporting means and pattern supporting means toward and from the pressure means, means for automatically arresting the movement of the flask supporting means after the flask supporting means and pattern supporting means have moved away from the pressure 70 means sufficiently to relieve the mold of pressure, and means whereby the flask supporting means may be released after the pattern supporting means has moved relatively thereto sufficiently to strip the pattern from the mold. 80

48. In a molding machine, the combination of a flask, flask supporting means, pattern supporting means, pressure means, means for moving the flask supporting 85 means and pattern supporting means toward and from the pressure means, means for automatically arresting the movement of the flask supporting means after the flask supporting means and pattern supporting means have moved away from the pressure means sufficiently to relieve the mold of pressure, and manually operable means for releasing the flask supporting means after the pattern supporting means 90 has moved relatively thereto to strip the pattern from the mold. 95

49. In a molding machine, the combination of pattern supporting means, pattern stripping means, a flask, pressure means, 100 means for moving the pattern supporting means and stripping means in unison with the flask toward the pressure means, means whereby the pressure on the mold may be relieved, and means whereby the pattern supporting means may be returned to normal position in advance of the pattern stripping means after the pressure on the mold is relieved. 105

50. In a molding machine, the combination 110 of a flask, flask supporting means, pattern supporting means, pattern stripping means, pressure means, means for moving the pattern supporting means toward and from the pressure means, means whereby the flask supporting means and pattern stripping means may be moved toward the pressure means in unison with the pattern supporting means, and means whereby the pattern supporting means may be returned to normal position in advance of the flask supporting means and pattern stripping means to strip the pattern from the mold. 115 12

This specification signed this 7th day of July, A. D. 1916.

WILLIAM H. NICHOLLS.
